UNITED STATES PATENT OFFICE.

CLARA B. YOUNG GEOFFROY, OF RIVER POINT, RHODE ISLAND.

DESIGN FOR A CHAIR.

Application filed September 19, 1928. Serial No. 28,213. Term of patent 3½ years.

To all whom it may concern:

Be it known that I, CLARA B. YOUNG GEOFFROY, a citizen of the United States of America, residing at River Point, in the county of Kent and State of Rhode Island, have invented a new, original, and ornamental Design for a Chair, of which the following is a specification, reference being had to the accompanying drawings, forming a part thereof.

The figure is a perspective view of the article showing my new design.

I claim:

The ornamental design for a chair as shown.

CLARA B. YOUNG GEOFFROY.
